HOT AIR FURNACE TYPE DRYING APPARATUS

Danah W. Johnston, Piqua, Ohio, assignor to Hartzell Industries, Inc., Piqua, Ohio, a corporation of Ohio

Application April 9, 1953, Serial No. 347,659

6 Claims. (Cl. 126—110)

This invention relates to a drying apparatus, and is a continuation-in-part of my co-pending application Serial No. 256,191, filed November 14, 1951, now Patent No. 2,716,975, dated September 6, 1955, and assigned to the same assignee as the instant application.

This invention is particularly concerned with a drying apparatus which is portable and which is especially adapted for the drying of farm crops and the like.

Many farm crops are advantageously dried before being marketed, processed or stored, such crops including grain crops, particularly corn, soy beans, rice, etc. and most forage crops. Other crops such as tobacco, fruits and vegetables may also be dried with the drier of the present invention, and in all cases the advantages obtain of a high speed of drying with the drying conditions being under control at all times.

The present invention has as a primary object the provision of an improved burner head in use for connection with a drying arrangement characterized by an angular construction which lends itself to being incorporated in the generally tubular drier structure.

Another object is an improved construction of the drier, by means of which a burner chamber is supported within an air duct so that expansion or contraction of the burner chamber does not impose stresses on the frame of the drier.

A still further object is the provision of a drier structure of the nature referred to in which there is an extremely efficient transfer of heat between the burner chamber and the air passing through the drier while at the same time the passage of the air through the drier is substantially unimpeded whereby greater volumes of heated air are available for drying purposes.

Another object of the present invention is the provision of a drying arrangement having a fan for blowing air through the drier in which the incoming cool air is so guided and directed that it forms a blanket over the hottest portions of the drier, thereby making the drier safer to use under all circumstances.

These and other objects and advantages will become more apparent upon reference to the following specification taken in connection with the accompanying drawings, in which:

Figure 1 is a side view of a drier constructed according to this invention, partly broken away to show the construction of the various elements thereof;

Figure 2 is an end elevational view looking in at the discharge end of the drier and which is the left end in Figure 1;

Figure 3 is a sectional view indicated by line 3—3 on Figure 1 showing more or less in detail the internal construction of the drier;

Figure 4 is a fragmentary sectional view indicated by line 4—4 on Figure 2 showing the configuration and arrangement of an air guide fin within the drier;

Figure 5 is a partial sectional view showing the novel construction of the burner which supplies heat for the drier; and

2

Figure 6 is a view similar to Figure 5 but showing a modified construction of the burner.

Referring to the drawings somewhat more in detail, the drier of this invention comprises a frame which may be made up of channel-shaped side members 10 suitably rigidly interconnected to form a unit and mounted on an axle structure 12 having supporting wheels 14.

At one end of the frame unit there is a clevis or yoke 15 by means of which the drier can be attached to a tractor. This same end of the supporting frame also preferably includes an adjustable pedestal member 18 for supporting the frame when it is disconnected from the tractor.

The drier proper includes a main cylindrical outer shell 20 supported on the frame of the drier and within which there is centrally located, in co-axial relation therewith, a cylindrical heating chamber or cartridge 22 closed at both ends, and within which there is a burner means that provides a flame that generates the heat for the unit.

The cartridge 22 is advantageously supported within shell 20 by means of a stack or exhaust connection 21 at the right end of the cartridge as it is viewed in Figure 1, and extending downwardly from the bottom of the cartridge 22 to shell 20. As will be seen by the dotted outline of the stack in Figure 3, this member is streamlined in cross-section so as to present a minimum resistance to airflow through shell 20 toward the left as it is viewed in Figures 1 and 3.

The outer surface of cartridge 22, as well as the outer surface of stack 21, preferably include the radially projecting fins 23 which may advantageously take the form of relatively small segments secured to the surfaces on which they are mounted as by welding. These fins are solely for the purpose of enhancing the extraction of heat from the cartridge and the stack.

At the right end of shell 20, as it is viewed in Figures 1 and 3, it is abutted by an orifice ring 28 in the inlet of which there is disposed a propeller or fan 30 carried on the end of the output shaft 32 of a motor 34 that is mounted on a platform in a spider-like frame 36 having the outwardly extending legs 38 which may be fixed about the periphery of orifice ring 28 by any suitable means.

It will be understood that the fan or propeller could be of any suitable type for propelling the required volume of air axially through shell 20, and that it could be arranged for being driven by an internal combustion engine rather than by the electric motor referred to if desired, and that it could be direct driven as illustrated, or driven by a belt from any desired power source.

A suitable screen shield 40 may be provided which prevents foreign matter from getting into the air stream being blown, and likewise provides a protective shield about the fan to prevent personnel injury.

Surrounding the right end of shell 20 and extending from the outer edge of orifice ring 28 toward the opposite end of the unit is an outer shell member 50 which has its left end in Figure 1 connected with the outer periphery of shell 20 as by the angle means at 52. It will be noted that shells 20 and 50 form an annular chamber that communicates with the lower open end of stack 21. This chamber serves to conduct exhaust gases from stack 21 to screened exhaust stack 54 at the top of the unit.

Spaced about outer shell 50 is a sheet 56 extending beyond the opposite end limits of shell 50 and having its edge portions secured to the frame of the unit by the connections indicated at 58 in Figure 2. The purpose of sheet 56 is to provide an insulating blanket of air about shell 50, and by arranging the sheet 56 as shown there will be a current of air flowing therethrough as represented by the arrows 60 on account of the operation of fan 30 which will maintain the outer surface of the unit cool enough to touch at any time.

Sheet 56 is maintained in properly spaced relation with

outer shell 50 by means of the spaced rib members which will be seen at 62 in Figure 2.

In the center at the bottom outer shell 50 is provided with an aperture 64 opening into a small chamber 66 closed by the detachable cover 68. This arrangement provides a ready means for cleaning soot and the like from the combustion chamber so that the drier can be maintained in efficient operation at all times.

The end of cartridge 22, opposite fan 30, is provided with a head 70 having a central aperture into which the discharge end of a burner head 72 extends. Burner head 72, according to the present invention and as will be seen in Figures 2 and 3, is of angular construction, and extending radially from the portion of the burner that projects through head 70 is a branch 74 extending through the side of shell 20 for connection with the motor operated pump and blower unit 76 and which may be, in itself, of conventional construction and provided with conventional controls.

The exact nature of burner 72 will be more clearly seen in Figure 5. In Figure 5 there is a conduit 78 through which oil is supplied under pressure to a conduit 80 leading to the twin nozzles 82 that discharge through the ring 84 into the interior of cartridge 22.

Igniter means in the form of electrode prongs 86 are supported in the proper position for igniting the fuel which is discharged from the nozzles as by means of the ceramic support 88 and to which are connected high tension leads 90 that extend from the ignition transformer of the burner unit.

The nozzle end of the burner has a supporting spider 92, while at its other end there is a rod 94 extending adjustably through head 96, and by means of which rod the nozzles 82 can be located in the proper position to insure efficient combustion.

A deflector member 95 mounted on rod 94 provides means for deflecting the blown air around the corner that connects the burner head with the branch 74. This arrangement promotes efficient operation of the burner.

The burner unit 76 also supplies combustion air which passes through branch 74, and then to the right about nozzles 82 and into cartridge 22.

The modified construction of the burner illustrated in Figure 6 is substantially identical with that shown in Figure 5, except that the Figure 6 modification only comprises a single nozzle. The supporting means for supporting the burners at the end of cartridge 22 is illustrated in Figure 6 wherein it will be seen to comprise a first mounting ring 100 secured to the end of the cartridge and have a substantial clearance about the burner head. A second ring 102 closely embraces the burner head and is bolted to mounting ring 100 by bolts 104. Packing means at 106 between the mounting rings completes the supporting structure for the burner head. The described arrangement is such that there can be substantial relative expansion and contraction between the burner head and the cartridge without undue strains being imposed on either thereof.

In Figures 1 through 4 it will be noted that inside shell 20 at the entrance end thereof there are disposed a plurality of air guide vanes 110 which, as will be seen in Figure 4, commence spirally of shell 20 and terminate axially thereof. The purpose of the vanes 110 is to straighten out the airflow from propeller 30 and to remove any rotational component therefrom so that the airflow through shell 20 is substantially all in the straight axial direction. This promotes efficient operation of the drier and reduces undesired turbulence and spin in the airstream issuing from the discharge end thereof.

A further device, according to this invention, for promoting efficient operation thereof takes the form of a deflector member 112, as best seen in Figures 1 and 2, which is located within the cartridge 22 on the burner side of the inlet of stack 21, and which causes the blast

from the burner to be deflected in the manner indicated by the arrows 114 in Figure 1. This brings the blast into contact with the entire inner surface of cartridge 22 thereby providing for efficient extraction of heat from the combustion gases from the burner.

In order to assist in supporting the cartridge 22, there is preferably provided a strap 116 extending upwardly from shell 20 to the bottom of the cartridge, as illustrated in Figures 1 and 2. Normally, the stack 21 will support cartridge 22 in its proper location, but strap 116 will provide additional support for the cartridge that is desirable, particularly in view of the portable nature of the drier unit.

It will be understood that suitable controls are provided for starting and stopping the propeller that drives air through the unit and for controlling the operation of the burner, and that such control means would include thermostats and safety controls. These controls have been illustrated, more or less, diagrammatically as being located within a covering hood 118 on the side of shell 20 at the discharge end of the unit. Since these controls are substantially conventional, however, no detailed description thereof is included herein. It will be understood, however, that the controls would include temperature regulating elements, high limit controls, stack controls, and no-flame controls, which last-mentioned might take the form of the electric eye 97.

It will be appreciated that fuel oil is only representative of the many fuels that could be used in the device of this invention; for example, natural gas, producer gas, L. P. gas, and liquid fuels such as kerosene and gasoline can also be used if convenient.

It will be understood that this invention is susceptible to modification in order to adapt it to different usages and conditions, and, accordingly, it is desired to comprehend such modifications within this invention as may fall within the scope of the appended claims.

I claim:

1. In a drier unit of the nature described; a horizontal outer shell open at both ends, a fan at one end of the outer shell to drive air therethrough, an inner shell closed at both ends mounted on the axis of said outer shell, an angular conduit having one portion extending radially through the wall of said outer shell and another portion extending axially into said inner shell at the end opposite said fan, a burner within said conduit at the end opening into said inner shell, an exhaust chamber formed around said outer shell adjacent the fan end thereof with the outer shell forming the inner wall of the chamber, said chamber terminating in an exhaust outlet at the top of the chamber at the end thereof opposite the fan, and a stack connecting the bottom of the inner shell at the fan end thereof with said chamber at the bottom thereof, said inner shell and said stack being provided with segmented fins extending therefrom in planes parallel with the direction of airflow through said outer shell.

2. In a drier unit of the nature described; a horizontal outer shell open at both ends, a fan at one end of the outer shell to drive air therethrough, an inner shell closed at both ends mounted on the axis of said outer shell, an angular conduit having one portion extending radially through the wall of said outer shell and another portion extending axially into said inner shell at the end opposite said fan, a burner within said conduit at the end opening into said inner shell, an exhaust chamber formed around said outer shell adjacent the fan end thereof with the outer shell forming the inner wall of the chamber, said chamber terminating in an exhaust outlet at the top, and a stack connecting the bottom of the inner shell at the fan end thereof with said chamber at the bottom thereof, said inner shell and said stack being provided with segmented fins extending therefrom in planes parallel with the direction of airflow through said outer shell, and said stack

being streamlined in configuration in horizontal cross-section.

3. In a drier unit of the nature described; a horizontal outer shell open at both ends, a fan at one end of the outer shell to drive air therethrough, an inner shell closed at both ends mounted on the axis of said outer shell, an angular conduit having one portion extending radially through the wall of said outer shell and another portion extending axially into said inner shell at the end opposite said fan, a burner within said conduit at the end opening into said inner shell, an exhaust chamber formed about said outer shell adjacent the fan end thereof with the outer shell forming the inner wall of the chamber, said chamber terminating in an exhaust outlet at the top, and a stack connecting the bottom of the inner shell at the fan end thereof with said chamber at the bottom thereof, said inner shell being provided with a deflector member extending upwardly at an angle from the bottom wall thereof between the burner and said stack serving to deflect the products of combustion upwardly in said inner shell before they enter said stack.

4. In a drier unit of the nature described; a horizontal outer shell open at both ends, a fan at one end of the outer shell to drive air therethrough, an inner shell closed at both ends mounted on the axis of said outer shell, an angular conduit having one portion extending radially through the wall of said outer shell and another portion extending axially into said inner shell at the end opposite said fan, a burner within said conduit at the end opening into said inner shell, an exhaust chamber formed around said outer shell adjacent the fan end thereof with the outer shell forming the inner wall of the chamber, said chamber terminating in an exhaust outlet at the top, and a stack connecting the bottom of the inner shell at the fan end thereof with said chamber at the bottom thereof, said outer shell being provided with guide vanes extending inwardly therefrom at the fan end thereof and comprising spiral portions adjacent the fan and axial portions extending therefrom whereby spin is removed from the blown air.

5. In a drier unit of the nature described; a horizontal outer shell open at both ends, a fan at one end of the outer shell to drive air therethrough, an inner shell closed at both ends mounted on the axis of said outer shell, an angular conduit having one portion extending radially

through the wall of said outer shell and another portion extending axially into said inner shell at the end opposite said fan, a burner within said conduit at the end opening into said inner shell, an exhaust chamber formed around said outer shell adjacent the fan end thereof with the outer shell forming the inner wall of the chamber, said chamber terminating in an exhaust outlet at the top, and a stack connecting the bottom of the inner shell at the fan end thereof with said chamber at the bottom thereof, the fan end of said outer shell being flared outwardly in the form of a venturi ring whereby operation of the fan will cause a sub-atmospheric pressure to exist about the periphery of said venturi ring, and a shroud sheet extending about and radially spaced from the outer wall of said exhaust chamber and extending axially to beyond the outer periphery of said venturi ring whereby air will be drawn through the space between said shroud sheet and the outer wall of the chamber by operation of said fan thereby preheating at least a portion of the air blown by the fan and also providing a cooling blanket about said exhaust chamber.

6. In combination in a drier, an outer shell and an inner shell mounted on the axis of said inner shell, a burner head in one end of said inner shell on the axis thereof, a supply conduit extending axially from said burner head and then at right angles through the side wall of said outer shell, the end of said inner shell being formed with an aperture for receiving said burner head with clearance, a flange on said shell also having clearance about said burner head, a flange fixed to said burner head axially spaced from the flange on the shell, packing between said flanges, and bolts connecting said flanges.
